UNITED STATES PATENT OFFICE.

PLINY P. PIPES, OF MANSFIELD, OHIO, ASSIGNOR TO THE OHIO BRASS COMPANY, OF MANSFIELD, OHIO, A CORPORATION OF NEW JERSEY.

RAIL BOND.

Application filed August 20, 1927. Serial No. 214,267.

My invention relates to rail bonds and particularly that type of bond arranged to be united to rails by welding, such as by a heating flame applied in the form of the electric 5 arc or the oxy-acetylene flame.

The object of my invention is to provide a bond which can be welded to the rail such that the union between the flexible body and the welding metal will be fixed and no relative 10 movement take place therebetween, but that such movement of the flexible body relative to the terminal parts will be outside the terminal member, as hereinafter described.

My invention resides in a new and novel 15 construction, combination and relation of the various parts which make up the rail bond and its terminals and which are described and shown in the specification and the drawing accompanying this specification.

20 In the drawing:

Fig. 1 is a side view of a single terminal of my bond, the other end of the cable having a terminal the same as shown in Fig. 1. The cable portion may be as long as desired.

25 Fig. 2 is a top view of the bond terminal shown in Fig. 1.

Fig. 3 is a view in partial section on the line 3—3 of Fig. 2.

30 Fig. 4 shows a U shaped bond applied to the adjacent ends of two rails. The view is shown in partial section for one terminal as along the line 3—3 of Fig. 2, with the welding metal applied and in full elevation for the other terminal.

35 In the preferred embodiment of my invention, I employ a body portion consisting of one or more flexible cables 1. The cable is cut to the length required, and each end of the body 1 is provided with a terminal 2 40 formed up out of sheet metal, such as copper or iron.

Under most conditions I prefer to use iron or steel for the terminal for the reason that it is not expensive as compared with copper, 45 and also forms a stronger union with the metal used in applying the bond to the rail and which is usually copper.

The terminal member 2 has a sleeve portion 3 which may encircle the entire body member 1 or a portion of it sufficient to securely grip the body 1 and a sleeve portion 4 composed of two layers of the metal crimped upon itself. I prefer to have the end of the body member 1 project above the terminal member 2

slightly, although this is not necessary, and I also have a small collar portion 5 projecting upwardly from the shelf 4. Interposed between the terminal 2 and the cable or cables 1 is a thin copper sleeve 6 projecting downwardly from the end of the sleeve portion 3. The thin copper sleeve 6 tends to prevent contact between the copper cable 1 and the steel terminal 2, and, therefore, acts as a cushion preventing the steel terminal from biting into the wires of the cable 1 when the terminal is compressed into position. The sleeve projecting downwardly tends to protect the strands where they enter the sleeve 3, and the tendency is to distribute vibration at this point over the distance which the sleeve 6 projects from the terminal rather than concentrating the vibration exactly at the end of the sleeve 3 thereby prolonging materially the life of the cables or cable 1 when used under severe vibration conditions, 75 as in steam road operation.

It is found where steel terminals are used with copper body members 1, that the application of the bond by the high temperature arc or oxy-acetylene flame causes the parts 80 to expand and the copper having a greater co-efficient of expansion than the steel, the tendency is for an almost imperceptible looseness between the body 1 and the terminal 2 when the parts have cooled. This small degree of looseness, however, tends to permit some of the vibration or relative movement of the cable with respect to the terminal to be transmitted up to the extreme end of the body members 1 where they unite to the welding metal, and the tendency is for the union between the cables and the welding metal to break or give way in due course of time.

I have found, however, that by uniting the wires of the cable together for the distance that they are confined within the terminal 2, and also uniting the outer layer of the stranded wires to the copper strip 6 that relative movement between the cable and the welding metal at the point of union is practically eliminated, and the relative movement takes place between the cable and the projecting end of the copper sleeve 6.

To bring about this improvement, I interpose between the copper sleeve 6 and the body member 1 a sleeve 7 of brazing material, 105 which will be fused during the operation of

applying a bond to a rail and will unite the strands or individual wires of the cable together and to the copper sleeve 6.

I do not find that the sleeve 7 is required when the terminal 2 is made of copper to nearly the extent as when it is made of steel or iron, for the reason that when made of copper the co-efficient of expansion of the terminal is equal to that of the cable.

10 In applying my improved bond, it is positioned on the rail 8 adjacent the end thereof and secured thereto by welding metal, preferably of copper fluxed with an alloy metal, such as silicon, manganese, phosphorus, etc., and this metal is melted and applied to the ends of the cable or cables 1 and the surface of the shelf member 4. With the type of bond shown in the drawing, it is preferable to use the oxy-acetylene flame in applying the heat which produces a temperature around 6300 degrees F. This high temperature flame is quite concentrated and fuses the end of the cables 1 and the upper surface of the terminal 2, and also fuses the welding or attaching metal which is applied in the form of a rod, and the rod is melted and is caught and retained upon the upper surface of the bond terminal and cable, forming the attaching head 9, which is also fused to the surface of the rail by means of the heating flame. This forms a mechanical and electrical union between the parts in which the welding metal 9 unites each part to the other.

15 The heat applied to the terminal and bond cable being very intense, is absorbed by the parts and conducted into the terminal and fuses the brazing sleeve 7, which then unites with the wires forming the cable 1 and with the inner surface of the sleeve 6, thereby uniting these parts together.

20 There are, of course, modifications which will be apparent to those skilled in the art, as for instance, there may be conditions under which the use of the sleeve 6 may be avoided, thereby uniting the wires of the stranded cable 1 directly to the inner surface of the

25 terminal 2 by means of the interposed brazing sleeve 7.

Having described my invention, I claim:

1. A rail bond comprising a body member 50 of a plurality of wires, a terminal member attached to each end of the body member and gripping the end of the body, a copper sleeve interposed between the terminal and body member and a sleeve of brazing material interposed between the copper sleeve and the body and arranged to fuse and unite with the copper sleeve and wires of the body member when the bond is applied to the rail.

2. A rail bond comprising a body member 55 of a plurality of wires, a ferrous terminal member attached to each end of the body member and gripping the end of the body, a copper sleeve interposed between the terminal and body member and a sleeve of brazing material interposed between the copper sleeve and the body and arranged to fuse and unite with the copper sleeve and wires of the body member when the bond is applied to the rail.

3. A rail bond comprising a body member 60 of a plurality of wires, a terminal member attached to each end of the body member and gripping the end of the body, a copper sleeve interposed between the terminal and body member and a sleeve of brazing material interposed between the copper sleeve and the body and arranged to fuse and unite with the copper sleeve and wires of the body member when the bond is applied to the rail.

4. A rail bond comprising a flexible body and a terminal formed up of a single sheet of ferrous metal and provided with a sleeve portion and a shelf portion projecting from the sleeve portion, a thin metal sleeve between 75 the terminal and body and a sleeve of brazing metal between the said thin sleeve and the body member and adapted to melt and unite the body member to the said thin sleeve when applying the bond.

5. In testimony whereof I affix my signature.

PLINY P. PIPES.
